(57) **CLAIM**

The ornamental design for a wall-mounted shelf extrusion, as shown and described.

DESCRIPTION

FIG. 1 is a front perspective view of a wall-mounted shelf extrusion showing my new design;

FIG. 2 is a rear perspective view thereof;

FIG. 3 is a right side view thereof;

FIG. 4 is a left side view thereof;

FIG. 5 is a top plan view thereof;

FIG. 6 is a bottom plan view thereof;

FIG. 7 is a front elevation view thereof; and,

FIG. 8 is a rear elevation view thereof.

The extrusion is shown with two symbolic breaks in its length. The appearance of any portion of the extrusion between the jagged break lines forms no part of the claimed design.

The broken lines show portions of the wall-mounted shelf extrusion that form no part of the claimed design.
